Application May 5, 1939, Serial No. 34,821

Term of patent 7 years

To all whom it may concern:

Be it known that I, Harry W. Longdin, a citizen of the United States, residing at Atlanta, in the county of De Kalb and State of Georgia, have invented a new, original, and ornamental Design for a Combined Filler and Suction Pipe Casing for Underground Storage Tanks, of which the following is a specification, reference being had to the accompanying drawing, forming part thereof.

Fig. 1 is an elevational view of a combined filler

and suction pipe casing for underground storage tanks showing my new design.

Fig. 2 is an elevational view at right angles to Fig. 1.

Fig. 3 is an elevational view opposite to Fig. 2.

Fig. 4 is a top plan view thereof.

I claim:

The ornamental design for a combined filler and suction pipe casing for underground storage tanks, as shown.

HARRY W. LONGDIN.
